(57) **CLAIM**

The ornamental design for a lamp, as shown and described.

DESCRIPTION

FIG. 1 is a perspective view of the front, top, and right side of the lamp;

FIG. 2 is a front view of the lamp;

FIG. 3 is a back view of the lamp;

FIG. 4 is a right side view of the lamp;

FIG. 5 is a left side view of the lamp;

FIG. 6 is a top view of the lamp;

FIG. 7 is a bottom view of the lamp;

FIG. 8 is a perspective view of the bottom and right side of the lamp; and,

FIG. 9 is a perspective view of the front, bottom, and left side of the lamp.

The broken lines in FIGS. 7-9 show portions of the lamp that form no part of the claimed design.
